US00D922392S

(12) **United States Design Patent** (10) **Patent No.:** **US D922,392 S**
Chan et al. (45) **Date of Patent:** **** Jun. 15, 2021**

(54) **CASE FOR PORTABLE ELECTRONIC COMPUTING DEVICE**

(71) Applicant: **Pioneer Square Brands, Inc.**, Seattle, WA (US)

(72) Inventors: **Jaimie Emerald Chan**, Renton, WA (US); **Michael Cooper Ferren**, Camas, WA (US); **Megan Elizabeth Zumel Manzano**, Seattle, WA (US); **Brian Lewis Piper**, Seattle, WA (US)

(73) Assignee: **PIONEER SQUARE BRANDS, INC.**, McLean, VA (US)

(**) Term: **15 Years**

(21) Appl. No.: **29/763,126**

(22) Filed: **Dec. 21, 2020**

(51) LOC (13) Cl. **14-02**

(52) U.S. Cl.

USPC **D14/440**

(57) **CLAIM**

The ornamental design for a case for portable electronic computing device, as shown and described.

DESCRIPTION

FIG. 1 is a top perspective view of a case for portable electronic computing device showing our new design.

FIG. 2 is a front elevational view thereof.

FIG. 3 is a rear elevational view thereof.

FIG. 4 is a right elevational view thereof.

FIG. 5 is a left elevational view thereof.

FIG. 6 is a top plan view thereof; and,

FIG. 7 is a bottom plan view thereof.

The features shown in broken lines in the drawing figures depict features that form no part of the claimed design.

1 Claim, 7 Drawing Sheets
